UNITED STATES PATENT OFFICE.

DOROTHEA C. PRATT, OF SUMMIT, NEW JERSEY.

ABDOMINAL SUPPORTER.

1,276,410.

Specification of Letters Patent. Patented Aug. 20, 1918.

Application filed March 23, 1918. Serial No. 224,162.

To all whom it may concern:

Be it known that I, DOROTHEA C. PRATT, a citizen of the United States, residing at Summit, in the county of Union and State 5 of New Jersey, have invented certain new and useful Improvements in Abdominal Supporters, of which the following is a full, clear, and exact description.

A large number of devices of the class 10 known as abdominal supporters have been designed and proposed, and in forms too numerous to classify or describe, except under the most general terms as single and double belts. The makers and designers of 15 these devices have, however, appeared to have been influenced by the desire to provide for mechanical aids to maternity or those afflicted with obesity and seem to have disregarded the comfort and convenience 20 not only of these but especially of others and slender persons who find it of advantage to wear such devices for various hygienic and other reasons.

Recognizing these existing conditions, I 25 have sought to devise a form of supporter which can be readily and economically manufactured, and which may be fitted or adjusted, applied and removed with the greatest facility and which, nevertheless, 30 will meet all the practical requirements of such devices however exacting their nature may be.

With this object in view I have produced the simple and efficient form of supporter 35 which is illustrated in the accompanying drawing, the features of novelty of which residing in the details of its construction and mode of use may be more readily understood and appreciated from the following specific rather than from any general description of its nature and purpose.

Figure 1 is a perspective view of my improved abdominal supporter, and

Fig. 2 an enlarged view of a portion of 45 the rear portion of the same.

As a whole the device comprises a broad band having side portions A and B composed of stout elastic webbing joined at the back to fabric sections C which may contain steels or bones, if so desired, and made substantially narrower to relieve the pressure on the spine. These rear fabric sections contain eyelet holes for laces D by which the main band may be adjusted to fit 55 snugly the form of the wearer.

The side portions A and B widen grad-

ually toward the front where they are connected with the fabric sections E containing steels or bones of somewhat substantial character and ending in interlocking edges 60 provided with hooks and eyes F by means of which the belt may be readily fastened around the abdomen.

With this band I employ a narrower belt 65 which is composed essentially of elastic webbing G terminating in fabric end sections H provided with vertical rows, two or more, of eyelets K and divided at one side where the edges are provided with loops L and hooks M.

The two bands are primarily adjusted by means of the laces, the outer or smaller belt being fastened by the laces passed through that row of eyelets which will give to the belt a tight fitting diameter. It is manifest 70 that the outer belt while normally adapted to cover and surround the lower portion of the broader band may be worn as low down as comfort requires.

The function of the outer belt is to afford 80 support to the sides of the abdomen and to hold the long bones or steels in the front or the wider band firmly against the lower abdomen. No single belt device of this kind 85 can ever be made to afford a permanent support of this nature.

It is obvious that adjustment of the device once made is more or less permanent. Either or both the inner and outer members 90 may be applied with the greatest ease, and while the device as a whole is virtually composed of four parts, they are permanently associated into one.

The means which I have adopted and 95 illustrated for uniting the outer belt and effecting its adjustment are desirable and convenient, but they are not of the essence of the invention, as others may be employed for the purpose.

What I claim is:

1. An abdominal supporter comprising in combination an inner broad band formed of sections of elastic webbing with fabric sections at front and rear, the rear sections being adapted to be secured and the length of 105 the band thereby adjusted by lacing, and the front sections containing bones or steels and adapted to interlock, of a narrower outer belt of elastic webbing sections having interlocking edges at one side, and fabric 110 sections at the rear with means thereon for attaching it at varying distances from its

ends to the rear of the inner belt and thereby adjusting its length.

2. An abdominal supporter comprising in combination an inner band formed of sections of elastic webbing with fabric sections at front and rear, the rear sections being adapted to be secured and adjusted by lacing and the front sections containing bones or steels and adapted to interlock, of a nar-

rower outer belt of elastic webbing sections 10 having interlocking edges at one side and fabric sections at the rear with vertical rows of perforations by which it may be attached to the inner belt by the lacing and adjusted as to length. 15

In testimony whereof I hereunto affix my signature.

DOROTHEA C. PRATT.
